CLAIM

The ornamental design for a hair dryer holder, as shown.

DESCRIPTION

FIG. 1 is an isometric view of the hair dryer holder, showing my new design;

FIG. 2 is a front elevational view thereof;

FIG. 3 is a top plan view thereof;

FIG. 4 is a rear view thereof;

FIG. 5 is a right side elevational view thereof, the left side elevational view being a mirror image thereof;

FIG. 6 is a top plan view of a variation thereof;

FIG. 7 is a right side elevational view of the variation of FIG. 6, the left side elevational view being a mirror image thereof;

FIG. 8 is a front elevational view of the variation of FIG. 6; and,

FIG. 9 is a rear elevational view of the variation of FIG. 6.
